LOUIS R. ALBERGER, OF GREENWICH, CONNECTICUT; BLANCHE DODGE ALBERGER AND SCOTT C. ROSS, OF NEW YORK, N. Y., AND ALVAN H. ALBERGER, OF HAMBURG, NEW YORK, EXECUTORS OF SAID LOUIS R. ALBERGER, DECEASED, ASSIGNORS TO ALBERGER CONDENSER COMPANY, A CORPORATION OF NEW YORK.

CENTRIFUGAL OR TURBINE PUMP.

1,009,819.

Specification of Letters Patent. Patented Nov. 28, 1911.

Application filed June 24, 1905. Serial No. 266,887.

To all whom it may concern:

Be it known that I, Louis R. Alberger, a citizen of the United States of America, and a resident of Greenwich, county of Fairfield, 5 State of Connecticut, have invented certain new and useful Improvements in Centrifugal or Turbine Pumps, of which the following is a specification.

This invention relates to a centrifugal or 10 turbine pump of the multistage variety, and more particularly to means for regulating the quantity of water or other liquid discharged by the pump.

My principal object is to construct a pump 15 of this class so that it will discharge at will varying quantities of water or other liquid while always running at practically a constant speed, and at the same time will consume power more or less in proportion to 20 the quantity of water being delivered, a pump of this character being particularly useful and desirable for the purpose of feeding steam boilers, for fire pumps, elevators, the water supply of cities, and similar and 25 other purposes.

A further object of the invention is to enable this result to be accomplished automatically in such a manner that a slight increase in the discharge pressure due to a lessened 30 demand for liquid will automatically reduce the quantity delivered and the power required, or vice versa.

The invention may be said to consist essentially in means for returning a portion of 35 the liquid from the delivery point of a pump, or of one stage to the entrance of the same pump or stage, or to the entrance to another stage, so that the head or pressure against each individual remaining stage will 40 be increased above what it was before and the discharge lessened without an increase of the final discharge head or pressure. Or, in other words, the invention consists essentially of means for modifying or controlling 45 the capability of a pump, or of one stage of a pump, to obtain a variable amount of discharge.

In the accompanying drawings illustrating 50 my invention Figure 1 is a view in elevation of a multistage pump driven by direct connection with an electric motor or steam turbine, and shows in section one form of valve or governor for automatically

regulating the flow and returning a portion of the liquid from the discharge point of 55 the last stage to the discharge of the next stage which is the same as the entrance to the last stage. Fig. 2 is a view partly in elevation and partly in section showing the return passage located between the discharge 60 point of the next to the last stage (designated 2) which is the entrance to the last stage, and the discharge point of the first stage (designated 4) and which is the same as the entrance to the stage designated 3. 65

Various methods have heretofore been employed in an effort to secure a variable and differential discharge with a constant speed of rotation. Ordinarily, these methods have consisted of throttling either the 70 delivery or the suction, or both, and by thus increasing the total head obtaining a reduced flow of liquid. But these methods are objectionable because in the case of the throttling of the delivery or discharge of the 75 pump, unless the pump is operating exactly under the head for which it is suited, the demand for power will at first be increased before it is reduced; and in the case of the throttling of the suction there is danger of 80 forming vapor or inducing a leakage of air under the vacuum produced; and obviously, either of these actions incidental to these two methods of obtaining a variable discharge must interfere greatly with the functions of 85 the pump.

In the annexed drawing, A denotes a steam turbine, or it may be an electric motor, or some other means for driving the pump, what is here illustrated being presented 90 simply by way of example and for the purpose of explanation. The pump illustrated is a multistage pump and has the stages 1, 2, 3 and 4. The stage numbered 4 is the first stage; that numbered 3 is the second stage; 95 that numbered 2 is the third stage; that numbered 1 is the last stage; or, in other words, the stage which is nearest the suction is considered as the first stage, while that nearest the discharge is treated as the 100 last stage.

5 denotes the suction pipe entering the stage 4, and 6 designates the delivery or discharge pipe issuing from the stage 1. A pipe 7 extends from the discharge passage 105 of the stage 1 to the discharge passage of

stage 2 which is the same as the inlet or suction of the stage 1. This pipe 7 provides for the return flow and transfer of pressure from the discharge of a stage to the inlet thereof, but it may run to another stage in the series. The result therefore which I have in view I accomplish in a very effective and simple manner by returning a portion of the water or other liquid from the delivery of one stage to the entrance of the same stage, and in this way the head or pressure against each individual remaining stage is increased above what it was before and the discharge is lessened without an increase of the final discharge head or pressure. Another way of stating the same thing would be to say that the delivery from the pump is expected to be, once the operation is fully established, against a constant pressure, the regulating valve serving to maintain the pressure constant, and variations in the duty of the pump with reference to its capacity being only in the quantity of water delivered. The advantages secured by this arrangement are very evident and of great importance. The return passage 7 is provided with a valve device, either a hand valve or an automatic valve. One form of the latter is illustrated in the drawing and will be presently described. When the return passage is closed the full amount of liquid which the discharge 6 is capable of delivering will be finally discharged; and none at all will be discharged when the return pipe is fully opened so as to allow the return flow to take place to the entire capacity of pipe 7, it being remembered that at this time the final discharge head will neither be increased nor decreased. The effect of having the return passage wide open is to cut out the last impeller of the series leaving the remaining impeller units to perform the same duty as they performed when said last impeller was in service, the pump delivering as a whole a correspondingly diminished amount of water. Of course, when the return passage is closed only partially, that is to say, only what will be less than sufficient to cut out the whole duty of the last impeller, it is evident that the impeller will still do a part of its work. By my improved arrangement the final head or pressure is not increased, and there is no vacuum produced in the suction over that normally existent and due to the lift or friction in the supply pipe. When the discharge is reduced in quantity the power consumed in the operation of the pump is also reduced and the pump may therefore be considered a practical and economical device for a number of purposes. Inasmuch as the return passage 7 may be provided with a hand valve, an automatic valve, or some other suitable controlling device, it is evident that the regulation of the flow and

pressure may be controlled manually or by the pressure in the discharge pipe. In order to more fully illustrate this last idea, I have represented the return pipe 7 as provided with a valve chamber 8, wherein is a valve 9. Upon the valve chamber 8 is a diaphragm chamber 10 containing a diaphragm 11, which divides the chamber into two compartments, the lower of which, as 12, connects with the discharge 6 through a pipe 13. On the opposite side of said diaphragm is a stem 14 associated with levers 15 against which bear springs 16. When the pressure on the under side of the diaphragm 11 in the compartment 12, through pipe 13, increases sufficiently to lift the stem 14 and overcome the pressure of the springs 16, the valve will be free to open under the pressure in the return pipe 7, the result of which will be that liquid will flow from the delivery of stage 1 to the discharge of stage 2 and likewise to the entrance of stage 1. Thus the pressure-operated valve 9 is connected with the delivery pipe 6 so that as the pressure in the latter increases, due to a lessened demand for water, the valve 9 will be opened to a greater or less extent, and in consequence of the return flow thus permitted, the discharge flow through pipe 6 will be reduced. On the other hand, it will be evident that as the pressure in the pipe 6 decreases the valve 9 will close again. Thus we have an automatic regulation of the return flow, and consequently of the discharge so that a variable quantity of water is discharged at various times, and as a portion of the liquid is taken from the delivery of stage 1 and transferred to the entrance of this stage, at the same time the discharge is lessened.

In boiler feeding operations the return pipe may have its valve operated by a fireman or other employee, or as is often the case in large installations of boilers where there is a large number of boilers, each having a feed pipe and valve, the fireman may manipulate the valve on the feed pipe at the boiler, and a slight rise or fall of pressure in the main feed pipe or delivery of the pump will act accordingly upon the automatic valve in the return pipe and perfectly control the discharge of water from the pump as I have already hereinabove fully explained.

In fire service the improved device constituting my present invention will serve to relieve strain upon the hose or piping in case there should be a sudden stoppage of opening; and on elevator work, where there is an intermittent demand for water, my improvement will avoid the constant stopping and starting of the pump to meet the demand. With electrically-driven pumps this starting and stopping at frequent intervals calls for a large excess flow of electric current at the

times of starting up, and results not only in an extremely irregular and expensive demand for current, but involves a considerable wear and tear on the apparatus.

5 I have stated that the pipe for the return flow of water or other liquid may connect the delivery of one stage with the entrance of the same stage, and this is preferable and usual with pumps that require a delicate and close regulation of pressure, but there are cases where a wider range is allowable, and in such cases the return may connect with the entrance of any stage of the pump, provided, however, that the return does not 10 include all the stages, for then the essence of the invention would be defeated. It is obvious moreover that the return may connect the delivery of one of the stages, say a second stage of a four-stage pump, with 15 the entrance of the fourth stage, or which is the same thing, with the delivery of the third stage. To give another example, the delivery of the first stage may connect by a suitable pipe with the entrance to the third 20 stage, and in both these cases the return and transfer of pressure will still accomplish the object of my invention, which is primarily to throw out of commission or render inactive, either partially or entirely, any 25 one stage or any number of stages less than all of the stages of the pump. And further, when, instead of a series of stages, there are 30 what would more properly be called several pumps in series, running at a constant speed, the return passage or pipe may connect 35 the delivery of one pump with its suction, or the delivery of one pump with the suction or inlet of another pump, and accomplish the same result as I have herein 40 stated can be accomplished by connecting the delivery of one stage of a pump with the entrance to the same stage.

Having thus described my invention, what I claim as new and desire to secure by Letters Patent, is:—

1. The combination with a multistage centrifugal or turbine pump, of a return passage between the delivery of one stage and the delivery of another stage.

50 2. The combination with a multistage centrifugal or turbine pump, of a return

passage between the entrance to one stage and the entrance to another stage.

3. The combination with a multistage centrifugal or turbine pump, of a return 55 passage from the delivery of a stage to the delivery of another stage, said passage having means to regulate the transfer of pressure.

4. The combination with a multistage 60 centrifugal or turbine pump, whose stages are arranged in series, of a return passage for connecting the delivery of one member with the delivery of another member, and means whereby the transfer of pressure 65 through said passage is automatically controlled.

5. The combination with a multistage centrifugal or turbine pump, of means connecting the delivery of one of the stages 70 with the delivery of another of the stages, said means being provided with an automatic valve controlled by the pressure in the final discharge.

6. The combination with a multi-stage 75 turbine pump, of a return passage between the delivery of one stage and the delivery of another stage.

7. The combination with a multi-stage turbine pump, of a return passage from the 80 delivery of a stage to the delivery of another stage, said passage having means to regulate the transfer of pressure.

8. The combination with a multi-stage 85 turbine pump, whose stages are arranged in series, of a return passage for connecting the delivery of one member with the delivery of another member, and means whereby the transfer of pressure through said passage is automatically controlled. 90

9. The combination with a multi-stage turbine pump, of means connecting the delivery of one of the stages with the delivery 95 of another of the stages, said means being provided with an automatic valve controlled by the pressure in the final discharge.

Signed at New York city this 20th day of June 1905.
